(57) **CLAIM**

The ornamental design for the needle for intradermal injection, as shown and described.

DESCRIPTION

FIG. 1 is a perspective view of front, top and right side of the needle for intradermal injection showing my new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an explanatory view of usage thereof.

The broken lines shown are included for the purpose of illustrating the unclaimed portions of the needle for intradermal injection and form no part of the claimed design. Dotted and dashed lines mean boundaries between the claimed portion and the non-claimed portion, and form no part of the claimed design.
